UNITED STATES PATENT OFFICE

CLARENCE M. BRODNAX AND JOSEPH LOIZZO, OF BROOKLYN, NEW YORK

ELECTRIC HEATING UNIT

Application filed October 9, 1929. Serial No. 398,376.

Our invention relates to electric heaters of the immersion type, used for heating water or other liquids. It has for its main objects to provide a heater of high efficiency 5 in which the resistance element may readily be changed and which is adaptable to a great many uses. A further object is to provide a heater of such a construction that a perfect electrical contact is always maintained between the element and its supporting means. A still further object is to provide a heater of simple, compact construction, attractive appearance, and comparatively inexpensive to manufacture.

These and various other objects and advantages will be readily understood from the following description and from the accompanying drawing, in which

Fig. 1 is a cross-sectional side view,

Fig. 2 a bottom view,

Fig. 3 a rear end view, and

Fig. 4 a cross-sectional end view taken on line 4—4 in Fig. 1.

While the preferred embodiment described 25 herein and shown on the drawing is particularly adapted for use in a steam radiator, it will be understood that we do not wish to limit the invention to any specific use but intend to employ it for any purpose to which 30 it can be adapted. It will also be seen that various modifications might be made without departing from the scope of the invention.

Referring now to all the views, simultaneously, the heater consists of a tubular 35 casing 10 sealed at its outer end 11 and welded, or otherwise suitably secured, in a fitting 12. This fitting, which in this particular case is provided with a hexagonal body 13 and a threaded portion 14, is provided with a circular recess 15. The outer 40 end of this recess is provided with an internal thread in which a domed cap 16 fits.

The resistance element 17, which consists of a solid bar, is mounted between contact 45 members 18 and 19. These members are U shaped, and cupped so as to provide a perfect seat for the bar 17. The contact member 18 is mounted on a disc 20, made of electrical and heat insulating material, and is held in place by a screw 21 which also secures the

disc to a spacing rod 22. A tongue 23, formed on the contact member and engaging in a hole in the disc, locates the contact member in its correct position.

The contact member 19 is secured on the 55 end of a slideable, metal rod 24 by means of the nut 25. This rod is free to slide in the shouldered, insulating and heat resisting bushing 26 which is secured to the fitting 12 by screws 27 and 28. This bushing is also 60 secured to the spacing rod 22 by means of the nut 29. The outer end of the slideable rod 24 is provided with a threaded portion on which a nut 30 is secured and with a guide rod 31 on which a compression spring 65 32 is mounted. This spring is compressed between a washer 33 and an insulating disc 34 which is located in a seat formed in the cap 16. Wires 35 and 36, contained in the electric cord 37, are attached to the slideable 70 rod 24 by means of the nut 30, and to the spacing rod 22 by means of the nut 29. A plurality of holes 38 are drilled in the cap 16.

When the heater is in use the current passes through the wire 35, rod 24, contact 75 member 19, resistance element 17, contact member 18, spacing rod 22, and wire 36, the resistance offered by the element causing this to heat and thus heat the casing, from which the heat is supplied to the liquid in which 80 the heater is immersed.

By locating the compression spring as shown, it is not affected by the heat from the element; thus its effectiveness is not destroyed, as would otherwise be the case. The 85 air holes 38 further assist in keeping this spring cool. By using this spring proper contacts are always maintained between the element and the contact members, even should these fuse as is sometimes the case. 90 The compression of the spring may be increased or decreased by turning the cap 16.

Having described our invention, what we claim as new and wish to protect by Letters Patent is:

1. In an electric heater, a pipe fitting for attaching the heater to and supporting it in a radiator, a tubular casing adapted to extend transversely through the sections of a radiator, one end of said casing sealed and the 100

other end secured in the said fitting, a resistance bar supported between two contact members contained in said casing, said contact members secured on insulating discs, a spacing rod securing said discs in position, one of said contact members connecting the resistance bar with the spacing rod, and means for connecting said resistance bar and said spacing rod to an electric circuit.

10 2. In an electric heater, a pipe fitting for attaching the heater to and supporting it in a radiator, a tubular casing adapted to extend transversely through the sections of a radiator, one end of said casing sealed and the other end secured in the said fitting, a resistance bar supported between two contact members contained in said casing, said contact members secured on insulating discs, a spacing rod securing said discs in position, one of said contact members connecting the resistance bar with the spacing rod, the other contact member slideably mounted and actuated by a compression spring, and means for connecting said resistance bar and said spacing rod to an electric circuit.

15 3. In an electric heater, a pipe fitting for attaching the heater to and supporting it in a radiator, a tubular casing adapted to extend transversely through the sections of a radiator, one end of said casing sealed and the other end secured in the said fitting, a resistance bar supported between two contact members contained in said casing, said contact members secured on insulating discs, a spacing rod securing said discs in position, one of said contact members connecting the resistance bar with the spacing rod, the other contact member slideably mounted and actuated by a compression spring, said spring heat-insulated from the resistance bar by one of said discs, and means for connecting said resistance bar and said spacing rod to an electric circuit.

20 4. In an electric heater, a pipe fitting for attaching the heater to and supporting it in a radiator, a tubular casing adapted to extend transversely through the sections of a radiator, one end of said casing sealed and the other end secured in the said fitting, a resistance bar supported between two contact members, said contact members secured to insulating discs, a spacing rod connecting said discs, one of said contact members connecting the resistance bar with the spacing rod, all of said aforementioned parts contained in the tubular casing, the other contact member slideably mounted in one of said discs and actuated by a compression spring, means for connecting said resistance bar and said spacing rod to an electric circuit, and all of said last-mentioned parts contained in the fitting so as to be heat-insulated from the resistance bar.

CLARENCE M. BRODNAX.
